E. VINCKE

TILE AND METHOD OF PRODUCING SAME

Filed Feb. 24, 1923

UNITED STATES PATENT OFFICE.

ENRIQUE VINCKE, OF BARCELONA, SPAIN.

TITLE AND METHOD OF PRODUCING SAME.

Application filed February 24, 1923. Serial No. 620,955.

To all whom it may concern:

Be it known that I, ENRIQUE VINCKE, a citizen of the German Empire, residing at Barcelona, Spain, have invented certain new and useful Improvements in Tiles and Methods of Producing Same, of which the following is a specification.

This invention relates to tiles and like flooring units and to the method of producing the same.

An object of this invention is to provide a tile or other flooring units capable of being formed of cork whereby the elements constituting individual flooring units are arranged in reinforced relation to one another.

Another object of this invention is to afford the use of granules or other particles of cork bonded to one another to form the respective elements of the individual tiles.

Another feature of this invention is to provide an improved method of molding and otherwise treating bonded particles of cork to provide a fresh and substantially flat surface for the face of the flooring unit exposed to wear.

Pursuant to the invention, the individual tiles or other flooring units are formed by molding granules or other particles of cork adhered by a suitable bonding process to provide a base having dimensions co-extensive with the length and width of the individual flooring unit and having its exposed face formed of portions certain of which are spaced from one another and bonded integrally with the base and of a height in excess of the height of the resulting tile, the spaces between such portions being recessed, applying a similarly molded unit to have its integral portions extend within the aforesaid recesses of the first-named tile, saw-cutting the mutually interprojecting portions to thereby effect freshly cut surfaces and providing portions located in and filling the respective recesses and resulting in a tile having a substantially flat and smooth tread face.

Preferably, one of the pair of co-ordinated tiles may be subjected to a prolonged heat treatment or to other suitable treatment whereby the color of its portions are darkened in tone relatively to the portions of the other co-ordinate tile, to thereby provide alternate portions of light and dark colors for the designs of the individual tiles.

Further features and objects of the in-

vention will be more fully understood from the following descriptions and accompanying drawings, in which—

Fig. 1 is a perspective view of a resulting tile having alternate strips of different coloring;

Fig. 2 is a perspective view showing a tile formed under compression to have its integral strip portions extending in excess of the height of the tile;

Fig. 3 is a perspective view of a pair of co-ordinated tiles about to be applied to one another;

Fig. 4 is a perspective view showing a pair of co-ordinated tiles in juxtaposed relation and a saw applied to the same; and

Fig. 5 is a perspective view of a modified form of tile having a design of symmetrically arranged figures.

Referring to Fig. 1, the tile comprises the base portion 10 of integrally bonded material or granules or other particles of cork and having a width and length corresponding to the width and length of the individual tile as a whole; in Fig. 1, the tile is illustrated of square outline. On the exposed or tread surface of the tile 10 are disposed the strips of the tile in similitude to parquet flooring; in this instance, the strips are eight in number and the four strips 11^a, 11^b, 11^c, 11^d may be of darkened color in coloring contrast to the set of alternate strips 12^a, 12^b, 12^c, 12^d, of light color. By regulating the temperature of the heat treatment of cork, the color of the cork particles may be controlled in light, medium or dark tones. The outer boundary of the tile 10 at its exposed surface is molded to have the narrow edge portions 13, 14, 15 and 16 on the four respective sides.

Such tile may have the strip portions 11^a, 11^b, 11^c, 11^d, integral with the base 10, pursuant to the procedure set forth more fully hereinafter, and in such circumstance, the edge portions 13, 14, 15, 16 are of the same color tone and form a part of the tread surface when the tile is positioned on a floor. The base portion 10 is of the same color as the strips integral therewith but is not exposed to view when in position on a floor. In this particular tile illustrated in Fig. 1 the spaced strips 12^a, 12^b, 12^c, 12^d are not in integral formation with the base 10 or with the edge portions 13, 14, 15, 16 and are located on the upper face of the base 10 with

in the recesses between the strips 11^a, 11^b, 11^c, 11^d.

As appears from Fig. 2, pursuant to the preferred form of the present invention, the spaced strip portions 11^a, 11^b, 11^c, and 11^d, are molded to have a height in excess of the edge portions 13, 14, 15, 16 and have the recesses 17^a, 17^b, 17^c, 17^d, respectively of a depth corresponding substantially equally to the excess height of the strip portions 11^a, 11^b, 11^c and 11^d, above the edge portions 13, 14, 15, 16.

In Fig. 3 I have indicated a pair of co-ordinated tiles 20, 21 formed from a common mold as referred to in reference to Fig. 2, but one tile 20 is turned angularly 180 degrees relatively to the other tile 21 to present its integral strip portion 11^a in substantial alignment with the recess 17^d of the tile 21 and similarly the integral strip portion 11^b in alignment with the recess 17^c; similarly the integral strip portion 11^c in alignment with the recess 17^b and the integral strip portion 11^d in alignment with the recess 17^a, whereupon, as is indicated in Fig. 4, the tiles are brought in immediate juxtaposed contact to respectively locate the relief integral strip portions of one tile 20 extending into the respective recesses of the tile 21, and conversely the relief integral strip portions of the tile 21 extending into the recesses of the tile 20. A saw 22 or like severing tool is then applied on the line of cutting indicated by the severing line 23, 23, whereby the excess height of the integral strip portions 11^a, 11^b, 11^c, and 11^d, of the respective tiles 20, 21, are fresh cut and the severed excess portions located within the corresponding recesses of the respective tiles 20, 21, resulting in two tiles each having the common characteristics of the tile shown in Fig. 1.

If desired, the tile 20 may be subjected to a prolonged heat treatment to produce a darkened tone in the coloring of its parts and the tile 21 of lower heat treatment to produce in a lighter tone, whereby the tiles resulting from the co-ordination of such pair of molded tiles are respectively provided with strips of alternate coloring and edges of a tone corresponding to the strips in integral molded relation therewith.

The cutting by means of a saw or like severing means effects a smooth surface to the tread or exposed face of the strips, in similitude to strips of hardwood heretofore commonly employed in parquet and similar flooring.

The tiles are preferably formed of granules or particles of cork, subjected to a heat treatment and under pressure to effect the bonding of the cork particles to one another without the use of an adhesive; in such compression and bonding process, the volume of the particles may be compressed from an

original volume to a considerably reduced volume of unity, and the heat treatment is raised to the range of temperature whereby the natural gum and resonance are exuded from the interior of the cells of the cork to effect the bonding of the individual particles to one another.

From the above, it will be observed that each tile is formed of a base of integrally bonded composition cork, having the same length and width as the individual tile and that the alternate non-integral strip portions are seated mechanically secure within the recesses of the tile and also preferably adhesively held therein, resulting in a tile having the elements thereof which are exposed to wear, mechanically reinforced in mutual relation to one another.

The invention possesses the advantage of enabling a parquet or similar flooring to be laid by the use of relatively large units in concrete or cement.

The invention is further advantageous in material and labor and cost items of the production of the individual flooring units.

If desired, the molded cork product may be formed with integrally molded strip portions and the recesses may be filled with strips of wood or like material, which may be colored in contrast with the molded portions as desired. Upon laying tiles of contrasting colors in side-by-side positions on the floor the flooring resembles parqueting.

It will be understood that the design of the tile may be varied as desired, such as a central circular design 30, as indicated in Figure 5, and the ninety degree arc designs 31, 32, which preferably are located symmetrically within the whole contour of the tile 33, to provide for recesses and elevations in contraposition in a pair of co-ordinate tiles, similarly as hereinabove set forth, to afford the dual treatment of a pair of tiles of the same or different colors.

Whereas I have described my invention by reference to specific forms thereof, it will be understood that many changes and modifications may be made without departing from the spirit of the invention, as defined by the appended claims.

I claim.

1. A flooring unit comprising a base formed of particles of cork bonded as a unit, certain portions of which extend to the exposed surface of the unit and integrally bonded with said base, the exposed surface of said articles being provided with recesses and portions of suitable material located within said recesses.

2. A flooring unit comprising a base formed of composition cork to form a base and portions extending to the exposed surface of the unit, said portions being spaced from one another and further comprising edge portions in integrally bonded relation

with said base, and portions disposed between said spaced portions on the wearing surface of the unit.

3. A flooring unit comprising a base, spaced portions formed of particles of cork bonded to one another without the use of extraneous adhesive, and strips of cork disposed between said spaced portions of the base.
- 10 4. The method of forming a flooring unit comprising molding bases formed of bonded particles of cork, each base having portions spaced from one another on one face of said base and spaces intervening said portions, applying pairs of such bases to one another to locate the portions of one base in the recess of the other base and the portions of said other base in the recesses of the said one base, saw-cutting the respective portions of 20 the respective bases for the extent thereof within said spaces and thereby producing a

pair of bases, each having a substantially flat tread face and each tread face having a freshly cut surface.

5. The method of forming a flooring unit 25 comprising molding differently colored bases formed of bonded particles of cork, each base having portions spaced from one another on one face of said base and spaces intervening said portions, applying pairs of such 30 bases to one another to locate the portions of one base in the recess of the other base and the portions of said other base in the recesses of the said one base, saw-cutting the respective portions of the respective bases 35 for the extent thereof within said spaces and thereby producing a pair of bases, each having a substantially flat tread face and each face having a freshly cut surface.

In testimony whereof I have signed this 40 specification this 27th day of January, 1923.

ENRIQUE VINCKE.
